UNITED STATES PATENT OFFICE.

CHARLES T. ANDERSON, OF CLARKSBURG, MARYLAND.

WASHING-MACHINE.

SPECIFICATION forming part of Letters Patent No. 379,263, dated March 13, 1888.

Application filed June 10, 1887. Serial No. 240,938. (No model.)

To all whom it may concern:

Be it known that I, CHARLES T. ANDERSON, a citizen of the United States, residing at Clarksburg, in the county of Montgomery and 5 State of Maryland, have invented certain new and useful Improvements in Washing-Machines; and I do hereby declare the following to be a full, clear, and exact description of the invention, such as will enable others skilled in 10 the art to which it appertains to make and use the same.

This invention relates to improvements in washing-machines of that class in which the clothes are pressed between two reciprocating 15 faces.

My improved washing-machine consists, essentially, of a box or clothes-receptacle having a bottom of curved shape for a portion of its width and supported upon suitable legs, a 20 pair of longitudinal rocking rubbers pivotally mounted in the ends of the box and each having a longitudinally-extending rib or rubber, one of which is provided with a corrugated upper face, while the other has a corrugated 25 under face, a longitudinal slot or opening being provided in each rocker below and above the rubber rib to permit of the passage of water during the reciprocation of the rubbers, said rubbers being at each end pivotally connected together and to a hand operating frame 30 or lever pivoted in the framing, a strip or valve extending longitudinally of and pivoted to the outer face of one of said rockers or rubbers to close the lower portion thereof as said rubber 35 moves outward and cause the projection of the water upward and over upon the clothes, and a strip secured to the outer face of said rubber to limit the outward movement of the valve and retain the clothes between the 40 rubbers.

In the accompanying drawings, Figure 1 represents a transverse sectional view of my improved washing-machine. Fig. 2 represents a detail perspective view of one of the 45 rockers and parts connected thereto. Fig. 3 represents a sectional end elevation of a rocker.

1 represents the supporting-legs; 2, the box within which the clothes to be washed, the 50 water, and the rocking rubbers are contained. The bottom of the box is of upwardly-curved shape for a portion of its length rearwardly,

as shown at 5, from whence it extends in a straight line to its rear, as shown at 6.

7 represents a bottom, preferably of galvanized iron or other suitable metal, of similar shape in cross-section to the contour of the bottom edge of the box. The rear wall, 8, of the box extends vertically in an inwardly-flaring or angular direction, while the front wall, 9, extends downwardly and outwardly, as shown.

10 represents the rear and 11 the front rubber. These rubbers each consist of a pair of vertical end pieces or standards, 12, which 65 extend above the top of the box, a longitudinal top bracing-strip, 13, a longitudinal bottom bracing-strip, 14, and an interposed rubber strip or rib, 15 and 16, slots or openings being left between said rubbing-rib and the 70 strips above and beneath the same, and also beneath the lower strip, to permit of the passage of water therethrough. The top strip, 13, on the rear rubber is either of a width sufficient to form a closed back to said rubber, to 75 receive the "wash" of the water as the rubbers are reciprocated and throw such water back upon the clothes in the box, as shown in Figs. 3, or it may be of less width, as shown in Figs. 1 and 2.

The rear rubber has pivotal bearing at its bottom in the ends of the box on a metallic brace-rod, 17, extending across said rubber and through the end standards or arms of said rubber. The front rubber, 11, is connected 85 with and has pivotal bearing at or near its top in the ends of the box by means of a brace-rod, 18, which may either be passed directly through the end standards or arms of said rubber or connected therewith with capability of ready removal therefrom by means of eyes or staples 19, attached to said end standards, the rod 18 in such case passing through said eyes or staples 19 into the end pieces with capability of free rocking movement therein. 95 Each opposite pair of standards 12 is pivotally connected together and to the hand grasp or frame 20, which is pivoted at 21 in the outwardly-extending portions of the top part of the box by pivot arms or links 22 22, so that 100 as said hand grasp, frame, or lever 20 is rocked inwardly on its pivotal bearings the upper portions of the rubbers will be pushed rearwardly and said rubbers separated from each

other, while when said hand grasp or lever is drawn forwardly said rubbers will be rocked into juxtaposition with each other and the rubbing-ribs 15 16 brought nearly together.

5 The rubbing-strip 15 on the rear rubber has an angular or bevel shaped corrugated top face, 23, while the rubbing-rib 16 on the front rubber has a correspondingly-shaped under face, 24; consequently as the rubbers are brought into operative position these corrugated faces are brought opposite each other one above the other, so as to operate upon reverse sides of the clothing being washed.

The front rubber depends in the box some what lower than the rear rubber, and when reciprocated will travel upward in the arc of a circle, its bottom traveling across the curved or dish-shaped portion of the bottom and in close proximity thereto, so as to carry the clothes resting on the bottom of the box upward into operative contact with the rubbing-ribs. As the hand-grasp is drawn toward the operator standing in front thereof, the operative part of the front rubber will, through the intervention of the pivotal connecting arms or links, be carried inwardly and upwardly, while the rear rubber will be rocked upon the pivots at its bottom and be drawn inwardly and downwardly to meet the ascending front rubber. It will thus be seen that the reversely-corrugated faces of the respective rubbing-ribs will be thereby brought into opposing positions, so as to operate upon reverse sides of the fabric under treatment.

35 25 represents a valve composed of a strip of metal extending longitudinally across and hinged or pivoted, as at 26, to the lower portion of the front rubber, so as to swing freely thereon as the rubbers are reciprocated.

40 27 represents a strip of metal extending across the longitudinal plane of said hinged strip or valve 25 and secured at its ends, as at 28, to the rubber, to limit the extent of opening of said valve. As the respective rubbers are oscillated into operative position this valve 25 swings open upon its hinge or pivot and permits of the passage into the front part of the box and through the open lower portion of the front rubber of any excess of water there 50 may be rearwardly of the front rubber. Then, as the hand-grasp is reciprocated to separate the rubbers, as the front rubber rocks forwardly the valve-plate 25 swings against and closes the slots or openings in the lower portion of the front rubber, and as said front rubber is rocked to its extreme forward position, there being no other escape for the water between the front of the rubber and the front

50 wall of the box, such water is forced over the top of the front rubber, and also through the slot above the rubbing-rib thereon, upon the clothing between the respective rubbers. By this means a constant circulation of the water contained in the box and agitation and displacement and change in position of the 65 clothes are secured, the result being, in connection with the peculiar construction and mode of operation of the rubbers, a rapid and thorough cleansing of the clothes.

When the rubbers or rockers are provided 70 with corrugated or grooved ribs 14 and 29, as represented in Fig. 1, said ribs on each rubber will, as the rubbers are rocked together, as represented in Fig. 1, approach each other and exert a rubbing and squeezing action upon 75 the clothes, thereby assisting in forcing water through such clothes and also assisting in their cleansing.

Having now described my invention, what I claim is—

1. A washing-machine comprising a box or case, a pair of vertical reciprocating rubbers pivotally journaled within said box and having rubbing ribs provided with opposing corrugated faces, having also longitudinal slots 85 or openings to permit of the passage of water through said rubbers, and upwardly-extending end pieces, an operating hand grasp or lever having pivotal bearing on the box-frame, links or arms pivotally connecting said rubbers together and to the hand-grasp, and a valve-plate hinged to the outer face of the front rubber, substantially as and for the purpose set forth.

2. In a washing-machine, a box having a 95 metallic bottom having a concaved front portion, a pair of rubbers vertically supported within said box upon pivot-bearings and having alternating slatted and slotted lower portions and inwardly-extending rubbing-ribs 100 having oppositely-corrugated rubbing-surfaces, a hand operating device, links or arms pivotally connecting said rubbers together and to the operating device, and a valve-plate hinged to the front face of the front rubber to 105 automatically close the open lower portion thereof upon said rubber being reciprocated forwardly and force the water upwardly and over upon the clothes between the two rubbers, substantially as set forth.

In testimony whereof I affix my signature in presence of two witnesses.

CHARLES T. ANDERSON.
